UNITED STATES PATENT OFFICE

JOHN HOLTZMAN, OF NEW YORK, N. Y.

AERIAL TOY DRIVE

Application filed December 18, 1924. Serial No. 756,718.

This invention relates to toys, particularly to types illustrative of aerial navigation and which are actuated by a self contained motor.

One of the features of the invention is in 5 the provision of means for disconnecting the propeller shaft from the motor-drive and coincidentally set a trigger to engage the motor spring when stressed.

Another aim is to provide means for stressing 10 the motor spring during the disengagement of the propeller shaft, the spring being released upon re-engagement of the propeller shaft with motor.

A further object is to utilize the propeller 15 as a governor or regulator for the motor, preventing it from attaining excessive speed.

These and other purposes which include, a 20 novel mechanical movement which may be adapted for other devices, an attractive toy 25 calculated to amuse, interest and instruct novices in mechanics and aeronautics, and a miniature flying machine, are accomplished by the novel construction, combination and arrangement of parts herein described, here- 30 after claimed, and illustrated in the accom- 35 panying drawing, constituting an important part of this disclosure, and in which:—

Figure 1 is a side elevational view of an 35 embodiment of the device, shown with the 40 motor at rest, as at the end of its run.

Figure 2 is a transverse sectional view taken 45 on approximately line 2—2 of Fig. 1.

Figure 3 is a similar sectional view taken 50 substantially on line 3—3 of Fig. 4.

Figure 4 is a partial side elevational view, 55 similar to Fig. 1, but showing the propeller shaft disengaged from the motor and the motor spring tensioned preliminary to opera- 60 tion.

Figure 5 is a perspective view of the device, 65 looking from above, the parts being ready for immediate actuation.

As shown in the drawing, the fuselage, 70 main frame or body of the device consists of a central longitudinal bar or rib 10, having at its rear a pair of spaced clips 11 and 12, by which is attached a support 13 raised at the rear and carrying a single flat plane 14 representing an angular profile, one of the points

of which are directed rearwardly, and an opposed pair extended laterally outward uniformly beyond the side of the bar, as best seen in Fig. 5.

At the front of the bar is a similar clip 15, 55 forming part of a downwardly extending bracket 16, having rearwardly extending plate portions 17 arranged in spaced parallel relation and provided with converging arms 18 fixed to the under side of the bar 10. 60

Other, wider clips 19, are attached to the bar in the rear of the bracket 16, and support a wing structure 20, extending equally from the sides of the bar.

Propeller blades 21 are fixed in a hub 22, 65 secured on a spindle 23 rotatable in a bearing formed in the plate 16, at a point near the hub and near its outer end in a bearing 24 formed in the end of a curved lever 25, the other end of which is pivoted to a bracket 26 70 fixed on the bar 10.

The inner extremity of the spindle 23 is seated in either of two sockets 27 or 28, 75 formed in a spring strip 29, secured at its lower end to projections on the rear of the side plates 17, and it is to be noted that this spring strip furnishes an effective thrust bearing of a yieldable nature, for the propeller.

Formed on the spindle 23 is a coarse 80 pitched worm or helix 30 to be driven by a gear 31, fixed on a transverse spindle 32, mounted in the plates 17, when the propeller spindle is horizontal, at which time its inner end will be disposed in the lower socket 28. 85

Also fixed on the spindle 32 is a pinion 33 and in mesh with it is a spur gear 34 fixed on a drum or spool 35, the spindle of which is journaled in the plates 17. 90

A bracket 37 at the rear of the bar 10 is 95 provided with an eye in which is engaged one end of a coiled tension spring 38, the other, forward end of the spring having a loop 39 engaging a cord or like flexible element 40, this cord being coiled several times around the drum 35 to provide efficient friction to drive the same, the cord then passing diagonally upward to a sheave 41, mounted on a bracket 42, fixed to the bar 10, below the clip 19, thence over another sheave 43 on a 100

similar bracket 44, likewise attached to the bar, the cord thereafter extending down by gravity to a spherical knob 45.

Fixed to the bar 10, rearwardly of the wing 20, is a bracket 46 in which is mounted a spindle 47 rigidly carrying a disc 48, and a hand lever 49 by which the spindle and disc may be turned, this lever having a guard as shown.

10 A link 50 is pivoted at its ends respectively to the disc and to the bent lever 25, so that the latter may be moved to raise or lower the propeller spindle 23, causing its front end to engage in either of the sockets 27 or 28, the latter insuring engagement of the worm 30 with the wheel 31, while if the spindle is raised to engage in the socket 27, the worm will be raised out of engagement at an angle as shown in Fig. 4.

20 Another bracket 51, fixed to the bar 10, has pivoted at its end a hook detent 52 engageable, when in one position, with the loop 39 of the spring and by which the spring may be held in a stressed condition.

23 The opposite end of the detent 52 is pivotally engaged by a link 53, also pivoted at its opposite end to the disc 48, being moved by the lever handle 49 into or out of engaging position.

30 In operation, the lever 49 is drawn rearwardly, disconnecting the propeller spindle from the motor drive gear 31 and at the same time extending the hook detent 52 into position to engage the spring link 39.

35 The spring is stressed or drawn out either by hand or by pulling on the knob 45 until the loop 39, is engaged with the detent, the motor gear train rotating in a reverse direction during this operation.

40 When this has been accomplished, the device is ready to fly and is set in operation by moving the lever 49 forwardly, this action liberating the spring to perform its function of pulling on the cord, and simultaneously 45 coupling the propeller spindle worm with the drawing gear.

45 The action of the propeller blades due to the friction of the air, is such as to retard an extreme rapid movement of the spring driven motor, controlling the same to a desirable rate of speed, and therefore assuring a flight of considerable length.

50 It will be understood that the mechanical devices disclosed are readily adapted for use 55 in connection with other structures of more important character than that of a toy and therefore are not to be thus limited.

55 Although I have described my improvements with considerable detail, and with respect to certain particular forms of my invention, I do not desire to be limited to such details since many changes and modifications may well be made without departing from the spirit and scope of my invention in its broadest aspect.

Having thus described my invention, what I claim as new and desire to secure by Letters Patent, is:

1. A mechanical toy comprising a bar, a bracket fixed to the bar, a spring actuated motor in the bracket, a spindle having a worm driven by one of the motor gears, means to engage or disengage the worm from the gear, and spring carried sockets to engage the end of the spindle in either of its adjusted positions. 70

2. A mechanical toy comprising a bar, a bracket on the bar, a spring actuated motor in the bracket, a spindle having a worm driven by one of the motor gears, means to engage or disengage the worm from the gear, and a spring strip having a pair of spaced sockets receptive of the spindle end to maintain the spindle in adjustment. 80

3. A mechanical toy comprising a bar, a bracket fixed to the bar, a spring actuated motor in the bracket, said motor having a drum, a cable wound on the drum, a tension spring attached to the opposite end of said bar, said spring engaging one end of the cable, a pull knob on the other end of the cable, means on said bar to engage said spring when extended, a spindle tiltingly mounted in the bracket to engage or disengage the worm from its driving gear, said means when engaging the worm coincidentally releasing the spring, and means to retain said spindle in either of its adjusted positions. 90

4. A mechanical toy comprising a bar, a bracket extending below the bar at one end thereof, a lever pivoted to said bar adjacent the bracket, a spindle journaled near its ends respectively in said bracket and said lever, a spring strip having spaced sockets receptive of the inner extremity of said spindle, means for shifting said lever to cause the spindle to engage in either socket, a worm on said spindle, a gear in said bracket adapted to drive the worm, and a spring motor in the bracket to energize said gear. 100

5. A mechanical toy comprising a bar, a bracket extending below the bar at one end thereof, a spring motor associated therewith, a worm driven by said motor, a lever pivoted to said bar adjacent the bracket, a spindle journaled near its ends respectively in said bracket and said lever, a spring strip having spaced sockets receptive of the inner extremity of said spindle, means for shifting said lever to cause the spindle to engage in either socket, a tension spring to actuate the motor, means for tensioning the spring, means for retaining the spring when tensioned, and means to release said spring coincidentally with engaging said worm. 110

6. A mechanical movement having the combination of a frame, a threaded spindle and gear revolvingly mounted in said frame 120

and in mesh with each other, a drum adjacent said gear, a cable engaging said drum, a spring engaging said cable to operate the spindle, a system of levers in the movement, and a hooked detent actuated by the levers and engaging one end of the spring and means actuated by the levers to engage and disengage the gear and spindle from mesh with each other and simultaneously release the spring from the hooked detent to operate the movement.

7. In a mechanical movement, the combination of a frame, a threaded spindle revolvably mounted in one end of the frame, a propeller fan fastened to said spindle, a gear train to actuate said spindle and propeller, a spring motor to drive said train, a hook member mounted in said frame for engaging one end of the spring when said spring is in its tensioned state, and manually operated means to disengage said propeller from operative engagement with the motor when said means are actuated in one direction and connect said propeller with said motor and simultaneously release said spring from the hook to operate the motor when said means is actuated in an opposite direction.

8. In a mechanical movement, the combination of a frame, a fan propeller revolvably mounted in the frame, a spring motor mounted in said frame to actuate the propeller, said motor including a gear train, a drum, a cable wound upon said drum, a spring arranged to pull said cable at one end thereof, and means to disengage said propeller from the motor to permit resetting the gearing in its initial position by pulling the cable at the other end.

9. In a mechanical movement, the combination of a frame, a revolvably mounted member in said frame, a spring motor for actuating said member, said motor comprising a gear train including a drum, a cable wound on said drum, a coiled spring with one end mounted in said frame and with the other arranged to pull the cable when said spring is tensioned to operate the gear train, and means to engage and disengage said spring to control actuation of the device.

10. In a mechanical movement, the combination of a frame, a gear train mounted in said frame, a spring to operate said train, a cable associated with said spring for setting the same in its operative position, means for engaging the spring when stressed, and means to release the spring to operate the movement.

11. In a mechanical toy aeroplane, the combination of a frame, a worm revolvably mounted in said frame, a fan propeller fastened to said worm, a gear meshing with the worm for actuating said propeller, a spring motor in the toy for driving said gear, and manually actuated means for disengaging

said worm from the gear while said spring motor is in operation.

12. In a mechanical movement, the combination of a frame, a gear train mounted in the frame, a spring in the frame to drive the train, a drum fastened to one of said gears, a cable wound upon said drum, said cable having two projecting ends, one end connected to the spring for actuating the gear train and the other end arranged to be pulled to set the spring to its initial operative position, and means to release the spring to start the movement.

13. In a mechanical movement comprising a frame, a spring motor mounted in said frame, a revolvably threaded spindle mounted in the frame actuated by said motor, a coiled spring to operate said motor, a drum associated with said motor, a cable wound upon said drum, a hook mounted in the frame for engaging said spring when said spring is in its stressed condition, a lever to disengage the spindle from the motor and to set the hook into position wherein it may engage the spring, said lever when actuated in the opposite direction being arranged to connect the spindle with the motor and simultaneously release the spring from the hook to operate the movement.

14. In a flying toy, the combination of a body member, wings on said member, a frame arranged forwardly of the wings, a worm shaft mounted in said frame with the axis thereof arranged in the direction of flight, a propeller fastened to said shaft, a gear meshing with said worm for driving said propeller, said gear arranged to be rotated in a vertical plane passing through the axis of said shaft, the axis of said gear shaft disposed horizontally, transverse to the worm shaft and approximately at the middle portion between its mountings, and a spring motor to drive said gear.

15. In a mechanical movement, the combination of a frame, a threaded spindle mounted in said frame, a gear train to actuate said spindle, a drum fastened to one of said gears, a cable wound upon said drum, a spring in the movement arranged to pull the cable to actuate the gear train, a lever actuated hook mounted in the frame to engage the spring when stressed, said lever arranged to disengage the spindle out of mesh with the gear train to permit said train to freely rotate when the cable is pulled at one of its ends, said lever being adapted to simultaneously engage said spindle with said gear train and release the spring from the hook to operate the device.

16. In an aeroplane toy, the combination of a body member, a transverse wing fastened to said body member, a bracket detachably connected to the front end of said member, said bracket comprising a pair of side walls and a front wall, a shaft mounted in

said front wall, means extending from said bracket to support the other end of said shaft, a propeller fastened to said shaft, a second shaft mounted in the side walls of said bracket and being parallel to the edges of the wing, a drum fastened to said second shaft and means interposed between said drum shaft and the propeller to actuate the same upon rotation of said drum.

- 10 17. In a toy aeroplane, the combination of a frame having a pair of side walls and an end wall, a member projecting from said frame having a free end, a spindle revolvably supported by said end wall and said member, 15 a propeller fastened to said spindle and means mounted on said spindle intermediate said wall and said member for actuating said propeller.

Signed at New York, in the county of New
20 York and State of New York this 17th day
of December, 1924.

JOHN HOLTZMAN.
